GRID GLOW TUBE

Dewey D. Knowles, Wilkinsburg, Pa., assignor to Westinghouse Electric & Manufacturing Company, East Pittsburgh, Pa., a corporation of Pennsylvania

Application September 23, 1933, Serial No. 690,700

4 Claims. (Cl. 175—354)

My invention relates to a vapor electric converter and particularly to an excitation system for such a converter.

In the operation of vapor electric converters, considerable trouble has been experienced because of inverse current carrying arcs or so-called back-fires in the converters. I have found that one of the principal causes of back-firing is the presence in the converter during the inverse or inactive half cycle of large quantities of ionized vapor.

It has heretofore been proposed to eliminate the creation of ionization during the inverse half cycle by providing a make-alive electrode operative at the beginning of each active half cycle to create a cathode spot in the converter. This make-alive system, however, has the disadvantage that at the crest of the forward current a relatively high current is present in make-alive electrode. This trouble is particularly prevalent in grid control devices such as grid-glow tubes, in which the main current carrying arc may be established late in the active half cycle.

It is an object of my invention to provide an excitation system requiring a relative low excitation current during that portion of the positive half cycle in which the main electrodes are substantially inactive and which are inoperative on the inverse half cycle.

It is a further object of my invention to provide an excitation system having a make-alive electrode for initiating the cathode spot and a keep-alive electrode for maintaining said spot until it is required to establish the arc between the main electrodes.

In the construction according to my invention, a vapor electric device is provided with a plurality of auxiliary or excitation anodes connected in parallel and preferably fed from the anode supply circuit through a suitable current limiting device.

Other objects and advantages of my invention will be apparent from the accompanying drawing in which the single figure is a schematic illustration of a grid-glow tube embodying my invention.

The apparatus according to my invention comprises a suitable evacuated chamber 1 having a cathode 2 of vaporizable material cooperating with a suitable anode 3. Suitable control grids 4 and 5 are interposed between the anode 3 and the cathode 2 to control the formation of the rectifying arc in the converter.

The grid 4 is a deionizing grid while grid 5 is provided with an outside terminal for connection to any suitable control system (not shown).

that changes and modifications can be made therein without departing from the true spirit of my invention or the scope of the appended claims.

5 I claim as my invention:

1. An arc discharge device comprising, a plurality of main electrodes, a control electrode for controlling the discharge between the main electrodes, a plurality of auxiliary electrodes for producing a cathode spot on one of said main electrodes, one of said auxiliary electrodes being operative to initiate a cathode spot and another to maintain said cathode spot until the control electrode operates to start the main arc, and means for inhibiting operation of the auxiliary electrodes when inverse potential is applied between said main electrodes.

10 2. An electrical conversion system comprising a source of alternating current, a direct current load fed thereby, a grid-controlled converter, a plurality of main electrodes in said converter at least one of said electrodes being of vaporizable material, a grid for controlling the discharge between said main electrodes, a 15 make-alive electrode for initiating a cathode spot on one of said main electrodes, a keep-alive electrode connected in parallel with said make-alive and a source of potential connected to said make-alive and keep-alive electrodes.

20 3. An electric valve comprising an anode, a cathode cooperating with said anode, a starting electrode in contact with said cathode, a keep-alive electrode spaced from said cathode, means 25 for applying positive potential to said starting electrode and said keep-alive electrode simul-

taneously with application of positive potential to said anode, said starting electrode acting to initiate a cathode spot on said cathode upon the application of positive potential to said electrodes, said keep-alive electrode being operative 5 to maintain said cathode spot during the application of positive potential thereto, means connected in series with said starting electrode for rendering said starting electrode inactive during operation of said keep-alive electrode, said means 10 preventing operation of said starting electrode during application of negative potential to said electrodes.

4. An electric valve comprising an anode, a cathode cooperating with said anode, a starting 15 electrode in contact with said cathode, a keep-alive electrode spaced from said cathode, means for applying positive potential to said starting electrode and said keep-alive electrode simultaneously with application of positive potential 20 to said anode, said starting electrode acting to initiate a cathode spot on said cathode upon the application of positive potential to said electrodes, said keep-alive electrode being operative 25 to maintain said cathode spot during the application of positive potential thereto, means connected in series with said starting electrode for rendering said starting electrode inactive during operation of said keep-alive electrode, said means 30 preventing operation of said starting electrode during application of negative potential to said electrodes, and a control electrode associated with said anode for controlling the formation of a current-carrying arc to said anode.
